UNITED STATES PATENT OFFICE

WALTER EVERETT MOLINS, OF DEPTFORD, LONDON, ENGLAND

MACHINE FOR CUTTING A MOVING WEB INTO STRIPS

Application filed September 8, 1927, Serial No. 218,347, and in Great Britain September 9, 1926.

This invention is for improvements in or relating to mechanism for automatically cutting a moving web of paper or like material into strips, and has for its object the provision of means whereby the leading edge of the traveling web may be moved out of engagement with the cutting blades after a strip has been severed therefrom.

It has been found that with a cutting mechanism which comprises a fixed blade and a rotatable blade, the leading edge of the travelling web of material is liable to cling to the movable blade after a strip has been severed therefrom and be carried around with the rotatable blade instead of being fed downwardly in a path tangential to the rotatable blade at the point where the same meets the fixed blade, and it is an object of the present invention to provide means which will ensure that the leading edge of the web of material is prevented from following the rotatable blade after a strip has been severed therefrom.

The present invention consists of a device for severing a travelling web of paper or like material into lengths which comprises a fixed blade, a rotatable blade adapted to co-operate therewith to effect a shearing action, and a stripper adapted to follow in close proximity to the rotatable blade, after each shearing operation and traverse a path substantially tangential to the path of the rotatable blade at the point where the same engages with the fixed blade.

Further, the present invention consists of a device for severing a travelling web of paper or like material into lengths which comprises a fixed blade, a rotatable blade adapted to co-operate therewith to effect a shearing action and a toothed stripper adapted to follow in close proximity to the rotatable blade and operable in such a manner that the free ends of the teeth of the stripper are automatically moved beyond the peripheral path of the rotatable blade after the same has sheared over the edge of the fixed blade and pass between teeth formed at the free end of a guide adapted to receive the leading edge of the web.

The invention is more particularly de-

scribed with reference to the accompanying drawings, wherein:—

Fig. 1 is a sectional side elevation of the device constructed according to the present invention.

55

Fig. 2 is a plan view of Fig. 1.

Fig. 3 is a front elevation of Fig. 1.

Fig. 4 is a detailed plan view of the rotary cutter illustrated in Fig. 1.

Fig. 5 is a side elevation of a modification 60 of the device illustrated in Fig. 1.

Fig. 6 is a detailed view of the rotary cutter and guide illustrated in Fig. 1 and

Fig. 7 is a section on the line *a*—*a* of Fig. 1.

One embodiment of the present invention 65 as illustrated in the drawings illustrates the invention applied to a machine adapted to envelop an article or a batch of articles in a U shaped block ended container formed from a strip of paper. The paper is continuously fed by a pair of rollers 1 and 2 from a reel downwardly through the bed 3 of the machine along which the article or batch of articles are fed in rapid succession. The

70

article or batch of articles are arranged to 75 engage with the web of material 4 and a cutting mechanism mounted between the reel of paper and the bed of the machine, is so timed as to sever a strip from the web when the article or batch of articles meets the web. Such a mechanism is described in U. S. Patent No. 1,468,246. The cutting mechanism 80 may comprise a fixed blade and a rotatable blade, and it is found with such cutting mechanism that the leading edge of the web of material is liable to adhere to the rotary blade and be deflected away from a guide 5 adapted to direct the leading edge of the web through the slot 6 in the bed of the machine.

85

According to the present invention a stripper 90 is operatively connected to the rotary blade and adapted to follow the path thereof, and move relatively thereto so as to cause the leading edge of the web to move out of engagement with the rotary blade and be fed 95 into a substantially vertical guide which directs the web through the slot formed in the bed of the machine.

Referring to Figs. 1, 2, 3, and 4, a cutting mechanism is mounted in a housing 7 sup- 100

ported upon pillars (not shown) mounted in any desired manner upon the bed 3 of the wrapping machine.

The travelling web of paper 4 is fed to the cutting mechanism from a reel by the pair of rollers 1 and 2. The roller 1 is carried upon a frame 8 which is adapted to swing in a horizontal plane about a pivot pin 9 so as to enable the roller 1 to move into and out of engagement with the roller 2, so as to permit the web to be adjusted correctly in the device.

After the web has been correctly aligned, the roller 1 is moved into position so as to clamp the web against the roller 2. The roller 2 is preferably carried in bearings adapted to yield under the pressure of the roller 1. The roller 1 is driven through a pinion from the main drive of the wrapping machine in such a manner that the web is fed to the cutting mechanism at the desired speed.

Mounted below the rollers 1 and 2 are a pair of guide members 10 and 11, which are adapted to feed the web in a vertical path to the cutting mechanism. The guide members 10 and 11 are constructed with vertical ribs 12 and 13, Fig. 7, arranged to give a transverse scallop to the paper in order to increase the vertical rigidity thereof. Situated directly below the said guide members 10 and 30 11 is a fixed blade 14 secured to the housing of the cutting mechanism so as to be adjustable towards and away from the web of paper.

Adapted to co-operate with the fixed blade 14 is a rotary blade 15 which is carried upon a spindle 16 in such a manner that the cutting edge thereof engages with the cutting edge of the fixed blade so as to effect a shearing action.

Mounted upon the said guide member 11 is 40 a resilient deflector plate 17 which is mounted so as to extend towards the edge of the fixed blade in such a manner that its leading edge is located in close proximity thereto, and in the path of the edge of the rotary blade. The 45 plane of the deflector plate 17 is inclined to the plane of the fixed blade and is located on that side thereof from which the rotatable blade approaches the fixed blade. The deflector plate 17 is controlled so that its movement towards the rotary blade may be limited to a predetermined distance.

The resilient deflector plate 17 hereinbefore described is preferably provided at its leading edge with a series of tongues 18, the purpose of which are described in U. S. Patent No. 1,631,879. The rotary blade is adapted to move in an anti-clockwise direction and is provided in advance of its cutting edge with a guard 19, which as the rotary blade 15 approaches the fixed blade 14 initially moves the web of paper and the deflector plate towards the edge of the fixed blade, whereupon the moving blade engages with the web and moves it together with the deflector plate 17 60 towards the fixed blade so as to move the

leading edge on the said deflector plate out of line with the leading edge of the fixed blade and so enable a strip to be cut from the web.

The leading edge of the deflector plate is 70 located close to the fixed blade so that as it is moved by the rotary blade it almost makes a scraping contact with the surface of the fixed blade.

As the rotary blade 15 moves over the edge 75 of the fixed blade, the tongues 18 of the deflector plate 17 move towards the axis of the rotary blade and deflect the freshly cut edge of the web away from the edge of the fixed blade.

In order to prevent the leading edge of the web from adhering to the surface of the rotary blade, there is mounted to the rear of the cutting edge of the rotary blade, a hinged stripper rod 20 pivoted at 21, and provided 80 with two fingers 22, the free ends of which lie substantially flush with the edge of the rotary blade 15. The stripper rod 20 is provided at its free end with a roller 23 adapted to ride over the surface of a fixed cam 24 as 85 the rotary blade 15 rotates. After the rotary blade has severed a strip from the travelling web of material, the hinged stripper rod 20 moves the fingers 22 so as to extend beyond the peripheral path of the rotary blade 15 and move the leading edge of the web out of 90 engagement with the rotary blade. The continued movement of the stripper rod 20 is arranged so that the free ends of the fingers 22 move in a substantially vertical plane tangential to the rotary blade when the same engages with the fixed blade and hold the leading edge 95 of the web in a substantially vertical plane and ensure that the same is fed into a vertical 100 guide 5 located directly above the slot 6 formed in the bed of the machine.

The upper edge of the vertical guide 5 which receives the leading edge of the web is located substantially upon the cylindrical surface traced by the rotary blade. As the free ends of the fingers 22 trace a path which extends beyond the peripheral path of the blade 110 the upper edge of the vertical guide 5 is provided with corresponding teeth which permit the free end of the fingers 22 to pass through the plane of the vertical guide.

The stripper rod 20 is spring controlled and is arranged to return to its initial position after the cam hereinbefore referred to has moved the fingers 22 into their extreme position.

Instead of the fingers 22 hereinbefore referred to, the stripper for removing the leading edge of the web out of engagement with the rotary blade and directing the same into the vertical guide may comprise the arrangement as illustrated in Figs. 5 and 6, wherein the stripper comprises a plate 25 mounted upon a spindle 26 which is operable by a 125

spring controlled link 27 arranged to engage with a fixed cam 28. The plate 25 extends approximately across the major portion of the blade 15 and is recessed at its central portion so as to engage with the vertical guide 5 which is shaped in the manner indicated.

Thus it will be seen that according to the present invention positive means are provided whereby the leading edge of the web is moved out of engagement with the edge of the rotary blade and is fed vertically through a guide which directs it through a slot in the bed of the machine without the possibility of the same fouling the edge of the slot or guide.

15 What I claim as my invention and desire to secure by Letters Patent is:—

1. In apparatus of the class described, the combination with a rotatable element adapted to engage a travelling web of sheet material, 20 of a guide for said web located adjacent the point of engagement between said web and said element, and means movable substantially in a straight line and tangentially of the rotatable element to convey said web from 25 said element to said guide.

2. In apparatus of the class described, the combination with a rotatable element adapted to engage a travelling web of sheet material, of a fixed guide for said web located adjacent 30 the point of engagement between said web and said element, and means rotatable with said element to guide said web from said element to said fixed guide, said means being movable in substantially a straight line tangential to the path of movement of said element.

3. A device for severing a travelling web of paper or like material into lengths which comprises a fixed blade, a rotatable blade arranged to cooperate therewith to effect a 40 shearing action and a stripper associated with the rotatable blade and operable to engage the leading edge of the web of material and strip the same from the rotatable blade after each 45 shearing operation, said stripper moving substantially in a straight line tangentially of the rotatable blade during engagement with the web.

4. A device for severing a travelling web 50 of paper or like material into lengths which comprises a fixed blade, a rotatable blade arranged to cooperate therewith to effect a shearing action and a stripper operable automatically to follow in close proximity to the 55 rotatable blade after each shearing operation, and to move in substantially a straight line path tangential to the path of the rotatable blade where the same engages with the fixed blade.

60 In testimony whereof I hereunto affix my signature.

WALTER EVERETT MOLINS.
